Primary Examiner — Ricky Pham(74) *Attorney, Agent, or Firm* — COZEN O'CONNOR(57) **CLAIM**

The ornamental design for a transparent bakeware as shown and described.

DESCRIPTION

FIG. 1 is a corner perspective view of a transparent bakeware in accordance with the claimed design;

FIG. 2 is a left side view thereof;

FIG. 3 is a right side view thereof;

FIG. 4 is a front view thereof;

FIG. 5 is a rear view thereof;

FIG. 6 is a top view thereof; and,

FIG. 7 is a bottom view thereof.

The portions shown in dashed lines are only for environmental structure and form no part of the claimed design.
